Primary Examiner — Austin Murphy(74) *Attorney, Agent, or Firm* — Muncy, Geissler, Olds & Lowe, PLLC(57) **CLAIM**

The ornamental design for a touch pen for a touch panel, as shown and described.

DESCRIPTION

FIG. 1 is a perspective view of a touch pen for a touch panel in accordance with my design;

FIG. 2 is a front view thereof;

FIG. 3 is a rear view thereof;

FIG. 4 is a top view thereof;

FIG. 5 is a bottom view thereof; and,

FIG. 6 is a front perspective view thereof showing the touch pen for touch panel shown in a position of use.

The broken lines shown in FIG. 6 represent unclaimed portions of the environment and form no part of the claimed design.

1 Claim, 4 Drawing Sheets**FIG. 1**

FIG. 2

FIG. 3

FIG. 4

FIG. 5

FIG. 6
